FOREIGN PATENT DOCUMENTS

GB 5003072 * 6/2016

Primary Examiner — Elizabeth A. Albert(74) *Attorney, Agent, or Firm* — Law Office of Michael O'Brien; Michael O'Brien(57) **CLAIM**

The ornamental design for a gardening pot, as shown and described.

DESCRIPTION

FIG. 1 is a front perspective view of a gardening pot showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in FIG. 6 and FIG. 7 are included to show portions of the gardening pot that form no part of the claimed design.

1 Claim, 5 Drawing Sheets(56)
